MANUAL PIPE BENDING VISE

Frederick J. McCalla, Harrisville, Mich.

Application February 26, 1947, Serial No. 731,113

3 Claims. (Cl. 153—38)

1

The present invention consists in novel and useful improvements in a pipe bending device and more specifically pertains to a portable, manually operable apparatus for quickly and easily imparting bends of any desired radius to pipe.

The principal objects of this invention reside in providing a pipe bending vise of an extremely portable, light weight and simplified construction; which has pipe engaging jaws readily adjusted to receive pipe; wherein the pipe engaged jaws may automatically adjust themselves radially to the curvature of a pipe during the process of bending the same; wherein novel and improved means are provided for applying the bending pressure to a pipe; and wherein arrangement is made to permit replacement of the jaws as wear and necessity dictate.

These, together with various ancillary objects of the invention which will later become apparent as the following description proceeds, are attained by this device; one embodiment of which has been illustrated by way of example only in the accompanying drawings; wherein:

Figure 1 is a top plan view showing the device applied to a pipe during the process of bending the same;

Figure 2 is a side elevational view of Figure 1, the pipe being omitted therefrom;

Figure 3 is a transverse vertical sectional view being taken substantially upon the section line 3—3 of Figure 1, a portion of the supporting legs being omitted in order to simplify the showing;

Figure 4 is a fragmentary detail view taken in vertical section substantially upon the section line 4—4 of Figure 1, and illustrating the manner of adjusting the pipe receiving jaws;

Figure 5 is a fragmentary detail view taken substantially upon the section line 5—5 of Figure 1 and in vertical section; and

Figure 6 is a fragmentary detail view taken in horizontal section substantially upon the section line 6—6 of Figure 3 and illustrating the construction of the pipe bending jaw.

Referring now more specifically to the accompanying drawings, wherein like numerals indicate similar parts throughout the various views, attention is directed first to Figure 2, wherein 10 designates a base plate having depending sockets 12 therefrom which detachably receive supporting legs or rods 14 in accordance with the conventional manner. As indicated in Figure 2, the base plate 10 is provided with an axial socket or bore extending from its upper surface, with which is associated a set screw 16 for retaining

2

in rotatably adjustable position upon said base plate, the supporting column 18 integrally depending from a head plate 20.

As shown more clearly in Figures 1, 2 and 4, the head plate 20 is provided with a centrally disposed tubular enlargement or boss 22 which is internally threaded to receive the correspondingly threaded portion of a rod 24, which is provided with a reduced extension 26 at one end 10 thereof and an enlarged cylindrical portion 28 at the opposite extremity.

The enlarged cylindrical portion 28 is provided with a plurality of diametrically disposed apertures 30 adapted to selectively receive a handle 32 by means of which the rod may be rotated and the extension 26 adjusted linearly of the head plate for a purpose to be later set forth.

As shown more clearly in Figures 1, 4 and 2, the head plate 20 is provided upon opposite sides of the tubular boss 22 with bifurcated flanges 34 and 36 at the opposite sides of said boss. The upper and lower furcations of the flanges 34 and 36 are provided with aligned bores or apertures adapted to receive a bolt 38 secured as by a nut 39 which bolt forms a pivot for an arm 40. As will be apparent, a similar pivot is provided in each of the flanges 34 and 36 and a pair of the arms 40 for oscillatively securing to said flanges for movement in a horizontal plane extending 20 through the bifurcations thereof. The outer ends of the arms 40 are pivotally connected as at 42 to the bifurcated ends 44 of C-shaped clamps 46, each provided with a V-shaped notch 48 upon their inner circumference.

As so far described, it will be seen that the C-shaped clamps or jaws 46 are adapted to engage a pipe 50 which is to be bent, and these jaws are pivoted upon the ends of the arms which in turn are pivotally connected to the head plate. Thus, as the pipe is bent about a central point between the two jaws in a manner to be subsequently set forth, the jaws and their supporting arms are permitted to oscillate about their pivot points in order to adjust themselves to the changed angularity occasioned by the changing curvature of the pipe.

As shown more clearly in Figures 1, 2 and 4, the bifurcated flanges 34 and 36 are provided with a plurality of appropriately spaced pairs of aligned bores 52 extending through both the upper and lower horizontal flanges 34 and 36, and which are adapted to be selectively aligned with an aperture or bore 54 in the arm 40. A fastening means comprising a pin 56 whose lower end is screw threaded 55 to engage the correspondingly threaded bore of

the lower flange, is provided with a headed portion 58 to which is attached a handle 60 whereby the pin may be selectively engaged with the above mentioned bores in order to secure each of the arms 40 in a predetermined angular relation to the adjusting rod 24. Obviously, the fastening pin 54 may be omitted, whereupon the arms are free to oscillate about their pivot points 36 as occasioned by the bending of the pipe 50.

Attention is now directed more specifically to Figures 1 and 6 for an understanding of the pipe bending jaw which is detachably secured upon the reduced extension 26 of the adjusting rod 24.

The bending jaw preferably consists of a unitary block 62 having a socket or bore 64 adapted to loosely receive the reduced extension 26 of the adjusting rod 24. Opposite the bore 64, the block 62 is provided with a concave surface 66, Figure 3, adapted to circumferentially engage the surface of the pipe 50 for applying pressure thereto. Within the concave surface 66, is disposed an intermediate zone in the form of a convex surface 68, Figure 6, adapted to engage the longitudinal surface of the pipe 50 and struck upon such a radius as will conveniently support and engage the pipe 50 as the latter is being bent in the position shown in Figure 1. It will thus be seen that the block 62 engages and supports the pipe 50 at circumferentially spaced points thereon, to distribute the strain of bending more evenly over the circumference of the pipe, and the convex surface 68 constitutes a guide or die limiting the radius about which the pipe is bent, to thereby prevent rupturing or straining of the pipe.

In order to detachably mount the block 62 upon the reduced extension 26, and thereby permit the selective use of other similar blocks but having different proportions of the concave and convex surfaces, the reduced extension 26 is provided with a recess or annular channel 70, positioned within the bore 64 as shown in Figure 6, and which channel is adapted to be engaged by a plurality of set screws 72, or the like, extending through the block 62 and loosely received within said channel. These set screws retain the blocks upon the reduced end 26, but permit a swivelling movement, of the block thereon, such as is necessary to permit the block to accommodate itself to slight mis-alignments of the pipe 50 with the tool.

From the foregoing, it is believed that the mode of operating the device will now be apparent. The head plate 20 may be either mounted in the support base 10, or in any other suitable support, and a pipe 50 disposed within the two pipe receiving jaws 46. The pipe bending jaw 62 is now applied to the reduced end 26 of the bending screw 24, and by rotation of the handle 32, the screw is driven inwardly of the head plate 20 and pressure applied by means of the jaw 62 to the pipe 50 intermediate the portions received by the C-shaped jaws 46. As continued pressure is applied, obviously the pipe 50 will be bent in the manner indicated in Figure 1, and if the fastening means 54 have been omitted, the arms 40 supporting the jaws 46 will freely oscillate and distribute the strain to the best advantage throughout the device. When, however, one or both of the arms 40 are locked in predetermined position

between the flanges 34 and 36 by means of the fastening means 54, the travel of the bending jaw 62 will still result in bending the pipe, the C-shaped jaws 46 now swivelling upon the ends 5 of the fixed arms 40.

Obviously, various modifications of the invention may be resorted to and consequently it is not desired to limit the protection sought to the exact construction shown and described, but all suitable modification and equivalents may be resorted to falling within the scope of the appended claims.

What I claim is:

1. A pipe bending device including a head plate, means for pivotally supporting said head plate, laterally extending bifurcated flanges on said head plate, a pair of pipe receiving jaws pivoted between said flanges and a pipe bending jaw linearly adjustable on said head plate, said pipe receiving jaws comprising C-shaped clamps, arms pivoted to said clamps and to said flanges at their extremities, and fastening means for securing said arms to both said flanges in pivotally adjusted position, said last means including a plurality of alined bores in said flanges, apertures in said arms and means selectively engaging said apertures and said alined bores.
2. The combination of claim 1, wherein said alined bores are displaced progressively greater distances from an axis perpendicular to the axis of rotation of said pipe bending jaw as they are displaced from the latter axis.
3. A pipe bending device including a head plate, means for pivotally supporting said head plate, laterally extending flanges on said head plate, a pair of pipe receiving jaws pivoted on said flanges and a pipe bending jaw linearly adjustable on said head plate, said pipe receiving jaws comprising C-shaped clamps, arms pivoted to said clamps and to said flanges at their extremities, and fastening means for securing said arms to said flanges in pivotally adjusted position, said last means including a plurality of bores displaced progressively greater distances from an axis perpendicular to the axis of rotation of said pipe bending jaw as they are displaced from the latter axis.
